(57) **CLAIM**

We claim the ornamental design for a portable inflatable bathtub with shampoo bowl and fold-out side and lower flap-like splash protection extensions for bedridden patients, as shown and described.

DESCRIPTION

FIG. 1 is a perspective view of a portable inflatable bathtub with shampoo bowl and fold-out side and lower flap-like splash protection extensions for bedridden patients, embodying the design of the present invention

FIG. 2 is a front elevational plan view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
